CHECKERWORK FOR MULTIZONE
REGENERATORSHans Pohl, Bad Tannistein, and Alfred Schack,
Dusseldorf, GermanyApplication September 11, 1931, Serial No. 562,346
In Germany September 25, 1930

1 Claim. (Cl. 263—51)

This invention relates to improvements in blast furnace air heaters, more especially multi-zone Cowper regenerators.

The most satisfactory checkerwork for regenerators hitherto known is that of the so-called multizone regenerator. This is characterized by the fact that in the hottest layer thick bricks are used having passages 6 to 8 inches wide which gradually lead over to a fine-meshed checkerwork 10 having passages down to one inch in width, the thickness of the walls being likewise gradually reduced. This arrangement is chosen for the following reasons:—

Wide passages are provided in the hot zone in 15 order to obtain a strong heat-radiation of the gas currents whereby the coefficient of heat transfer is considerably increased during the heating or gas period. Moreover wide passages are less subjected to softening. This kind of checker work 20 underlies to the following conditions of temperature:—

The wide passages in the hot zone result in a 25 relatively strong radiation and a relatively low speed of the gas currents. As taught by recent searches, a combustion gas containing carbon dioxide and water vapor delivers great amounts of heat by radiation at temperatures above 500° C. This radiation increases with increasing thickness of the layer of the radiating gas, and above 30 all with increasing temperature. In addition to this heat transfer by radiation a further amount of heat is delivered from the gas by contact with the surface to be heated (delivery by convection). In contradistinction to the heat transfer by radiation, the heat transfer by convection decreases 35 with increasing thickness of the gas layer, i. e. with increasing diameter of the passages and moreover depends upon the speed of the gas in such a way that the convection decreases and increases with the speed of the gas. Now as the 40 above-described checkerwork, besides the great width of the single passages, has a great free total cross-section, the streaming velocity of the gas and therewith the heat transfer by convection is 45 relatively small. Therefore the usual arrangement of wide passages in the hot layers results in a large heat transfer by radiation, and a small heat transfer by convection. As the heat transfer by radiation at the temperatures of 1000° C. and 50 more have coming into consideration is by far superior to that by convection, the total heat transfer during the gas period is a considerable one with the usual wide-meshed checkerwork.

Quite different are the conditions appearing 55 during the blast period. As the air does not con-

tain appreciable amounts of carbon dioxide and water vapor, the gas radiation does not take a noticeable part in the transfer of heat. Consequently the air current during the blast period of the regenerator absorbs heat by convection 60 only and, as the absorption of heat by convection, as above mentioned, decreases with the increasing diameter of the passages and decreases with decreasing velocity, the heat transfer during the blast period is small in the hot part of the regenerator. Strictly speaking not the transfer of heat or the passage of heat is concerned, but the coefficient of heat transfer, i. e. the heat transfer in calories per square meter and hour and per centigrade of difference between the temperatures. Assuming for the sake of simplicity a plant comprising two regenerators, of course the total heat transfer during the gas period per square meter of heating surface must be equal to the total heat transfer during the blast period per square 75 meter of heating surface. The above explained differences in the heat transfer then manifest themselves in that the difference between the temperatures of the heating gas and the surface to be heated is small owing to the high coefficient of 80 heat transfer and the difference between the temperatures of the heating surface and the blast is great owing to the small coefficient of heat transfer. These conditions of heat transfer practically mean that the average temperature of the bricks 85 in the described regenerators approaches the temperature of the gas and therefore is very high, whereas the temperature of the air remains relatively low. (See, for instance, equation No. 428 in the text-book by A. Schack "Der industrielle 90 Wärmeübergang", Düsseldorf, editor Stahl-Eisen.) This high brick temperature is dangerous and often results in destruction of the regenerator.

Having recognized these relations the inventors do away with such inconveniences by employing even in the hot zone narrow passages having a diameter of four inches or less. Hereby the rate of flow and therewith the coefficient of heat transfer by convection during the 100 gas and blast periods are increased. Simultaneously the radiation during the gas period decreases to such an extent, that all in all the coefficient of total heat transfer during the gas period is decreased and the coefficient of total 105 heat transfer during the blast period is considerably increased. The coefficients of heat transfer are in this manner approached to one another. As a rule, we have found that the passages in the hot zone should have a free cross- 110

sectional area aggregating less than the narrower passages in the colder zones and only 40 per cent. or less of the total cross-sectional area.

By reducing the width of the passages in the 5 hot zone in the manner herein described it is forthwith possible to reduce the temperature of the bricks as compared with the corresponding zone of a usual multizone regenerator which in all other respects is worked under the same conditions.

Besides the temperatures the coefficient of heat transit k (see equation 427 in the above-cited book by Schack) is decisive for the total heat transfer. This coefficient k is composed of 15 the two coefficients of heat transfer during the gas and blast period. It is always smaller than the smallest of the coefficients of heat transfer contained therein. Therefore with the multizone regenerators hitherto known the coefficient 20 of heat transit in the hot layers is small, although, as above described, the coefficient of heat transfer is great during the gas period; for the coefficient of heat transfer during the blast period is small in this regenerator and 25 therefore the coefficient of heat transit is still smaller. As according to this invention the coefficient of heat transfer during the blast period is considerably increased, it results that although the coefficient of heat transfer of the 30 gas is decreased the coefficient of heat transit and therewith the total heat transfer are increased by 50 per cent. and more. Accordingly a second advantage of our invention consists in the increase of the heat transit per 35 square meter of heating surface in the hottest parts. Furthermore according to this invention the heating surface per cubic meter of the space for containing the checkerwork is increased. Finally the stability of the checkerwork as compared with the old wide-meshed checkerwork is 40 increased.

As to-day in any case purified waste gas from the blast furnace is employed, there are no objections to the reduction in diameter of the 45 passages.

Accordingly the present invention consists in

reducing the size of the passages in the hotter zones, in which the temperature is from 800 to 1600° C., to such an extent that the total free cross-sectional area of the passages is not greater than 40% of the total cross-sectional area of the regenerator. In this way, the heat transfer coefficient for the air is increased relatively to the heat transfer coefficient for the gas. Further, the total heat transmitted and the total heating surface per cubic metre are considerably increased relatively to the usual construction of multi-zone Cowper regenerator. The checkerwork may contain a number of zones, each of which has narrower passages and thinner bricks than the previous one. This type of checkerwork can be used in all kinds of regenerators in which there is no likelihood of any great amount of clogging.

The invention is illustrated by way of example in the annexed drawing.

Fig. 1 is a vertical cross-section through the checker-work, and Fig. 2 is a cross section on the line 2-2 of Fig. 1.

a is a part of the checkerwork of the first zone of a regenerator, and *b* is a part of the second zone. In the first zone which is heated to temperatures of from 800 to 1600° C. the total cross-sectional area of the passages is less than 40% of the total cross-sectional area of the checkerwork, whilst in the second zone which is heated to temperatures lower than 800° C. the total cross-sectional area of the passages is more than 40% of the total cross-sectional area of the checkerwork.

We claim:—

Checkerwork for multizone regenerators, particularly air heaters with thick stones and wide passages in the hot zones and thinner stones with narrow passages in the colder zones in which the passages in the hot zones have a free cross-sectional area aggregating less than said narrower passages and only 40% or less of the total cross-sectional area.
